UNITED STATES PATENT OFFICE.

CHARLES S. COX, OF ELIZABETH, NEW JERSEY.

DRAWING INSTRUMENT.

SPECIFICATION forming part of Letters Patent No. 663,065, dated December 4, 1900.

Application filed January 4, 1899. Serial No. 701,098. (No model.)

To all whom it may concern:

Be it known that I, CHARLES S. COX, a citizen of the United States, and a resident of Elizabeth, Union county, State of New Jersey, have 5 invented a new and useful Drawing Instrument, of which the following description, taken in connection with the drawings herewith accompanying, is a specification.

This invention has for its object to provide 10 a cheap and simple drawing instrument that may be used as an ordinary T-square and also be capable of adjustment whereby a part thereof may be held in fixed connection with a drawing-board or other support and its 15 blade be guided and operated relative to said fixed or stationary part so as to have a uniform step-by-step movement over the drawing for the purpose of section-lining, shading, or otherwise. This object I secure by 20 means of the construction and arrangement of parts, as hereinafter set forth in detail, and pointed out in the claims.

Referring to the drawings, Figure 1 is a perspective view of a drawing instrument embodying my invention, the same being shown 25 in operative position in connection with a drawing-board. Fig. 2 is an enlarged perspective view of the instrument, showing the operating parts in full lines and the blade 30 and head in dotted lines. Fig. 3 is a detail view illustrating the action of certain parts, to be hereinafter referred to. Fig. 4 is a sectional view through the center of the instrument with the blade broken away, and Fig. 35 5 is a side view of the same.

To explain in detail, 1 represents the blade, and 2 the head, of an ordinary T-square. According to my invention I connect a bar 3 with the inner edge of the head 2 in a suitable 40 manner to permit of the latter, with its connected blade, having a sliding movement relative thereto. Any suitable means may be employed for securing such connection between the parts 2 and 3, a simple and desirable means 45 being the dovetail connection, as shown in the drawings. The said bar 3 is adapted to be held in fixed position relative to the drawing-board or other support on which the instrument is used, while the head and blade are 50 operated relative thereto, and is therefore provided in the present instance shown with pins 4 4 for securing detachable connection

with the edge of the drawing-board. The inner side of the bar 3 or that side adjacent to the head 2 is provided with a rack 5, secured 55 thereto, which is engaged by a pinion 6, located in a chamber or recess in the head 2. This pinion 6 is connected with an operating-spindle 7, which is supported in the head 2, with its upper end extending above the surface of the latter and provided with a milled head 8 as a convenient means for operating the same and the connected pinion. By this construction and arrangement of parts the instrument may be placed in proper position 65 upon a drawing-board, as shown in Fig. 1, and the bar 3 be secured in a fixed position relative thereto by simply pressing its pins 4 4 into the edge of the board, after which the operator may readily move the blade 1 70 over the drawing with a uniform step-by-step movement by turning the spindle 7, it being understood that the turning of the pinion relative to the stationary rack will cause a longitudinal movement of the head 2 and 75 its connected blade.

The distance of movement of the blade 1, which determines the space between the lines of the drawing, is of course regulated by the turning of the head 8, which is operated with 80 an intermittent movement. The operator readily becomes sufficiently expert in the manipulation of the instrument as to move the blade rapidly and with the greatest accuracy, being materially assisted in this by 85 reason of the hand resting upon or against the head 2 and being carried thereby. In some cases, however, and particularly in the case of beginners, it may be desirable to have a means for indicating accurately the distance 90 of each step-by-step movement of the blade. As a simple means for doing this I have provided the spindle 7 with a disk 9, having a series of notches 10 arranged at regular intervals apart, and have secured a spring-click 95 11 to the head 2, with its free end bearing against the periphery of said disk 9 and adapted to project into the notches therein. By this means it will be understood that as the spindle 7 is turned in the operation of 100 moving the blade 1 the spring-click 11, projecting into the successive notches in the disk 9, will indicate, both by sound and by the check to the movement of the spindle, the

distance between each of the notches, and thereby the proper distance of movement of the blade. In case it is desired to move the latter a greater distance than the space between each successive notch in the disk 9 the blade can be stopped at every alternate or other desired number of clicks. Any suitable means, however, for indicating the distance of the step-by-step movement of the blade other than that illustrated and described may be employed without departure from my invention.

The pins 4, with which the bar 3 is provided, are in the present instance shown loosely supported within recesses in said bar and provided with openings through which a rod 12 extends. This rod 12 is supported in a longitudinally-movable position in the bar 3, with one end 13 projecting beyond the end thereof as a means for operating the same and is formed with two bends or cam portions 14, adjacent to the pins 4, which act upon the latter when the rod is moved in one direction to force the ends of the same outward beyond the face of the bar, as shown by dotted lines in Fig. 3, and when the rod is moved in the opposite direction force the pin backward into their recesses, as indicated by full lines in said Fig. 3. The pins being thus movable, whereby they may be shielded when not in use, I consider the preferable construction, although they may be stationary, if desired.

The blade 1, as herein illustrated, is pivotally connected with the head 2, so as to be capable of being adjusted at any desired angle relative thereto, and as a means for holding said blade in fixed adjusted position I have provided the pivot-pin 15, which is supported in a vertically-stationary position in the head 2, with a cam-lever 16, and have interposed between the latter and the head 2 a cam washer or ring 17. By turning the lever 16 in the proper direction the blade 1 will be either clamped in fixed position or released for further adjustment. As a means to permit of the accurate adjustment of the blade relative to the head 2 I have provided the end of said blade with an index 18 and secured an index-pointer 19 in fixed position upon the head 2.

Having thus illustrated and described one practical embodiment of my invention, I wish it to be understood that the same may be more or less materially modified without departure from the spirit of the invention.

What I claim, and desire to secure by Letters Patent, is—

1. A combined T-square and section-liner, comprising a cross-head and connected blade, a bar having a sliding dovetail connection with said head and being provided with a rack on that edge located within the latter, a pin-

ion located within a recess in the cross-head and engaging with said rack, and an operating-spindle carried by the cross-head having connection with said pinion to operate the same and being arranged with one end projecting above the upper surface of the cross-head to be operated, substantially as and for the purpose set forth. 65

2. A combined T-square and section-liner, comprising a cross-head and connected blade, a bar having a sliding dovetail connection with said head and being provided with a rack on that edge located within the latter, a pinion located within a recess in the cross-head and engaging with said rack, an operating-spindle carried by the cross-head having connection with said pinion to operate the same 75 and being arranged with one end projecting above the upper surface of the cross-head to be operated, a second toothed or notched disk secured on said spindle at a point within the cross-head, and a spring-click engaging with 80 said toothed or notched disk, substantially as and for the purpose set forth. 85

3. A combined T-square and section-liner, comprising a cross-head and connected blade, a bar having a sliding connection with said head and provided with pins movably supported within recesses in one side thereof, means for engaging with and moving said pins to and from a position with their ends extending beyond the surface of the bar, and means 90 for operating the said head and connected blade with a step-by-step movement relative to said bar. 95

4. A combined T-square and section-liner, comprising a cross-head and connected blade, a bar having a sliding connection with said head and provided with a pin movably supported within a recess in one side thereof, a sliding rod supported by the cross-head having a bent or cam portion for engaging with 100 and moving said pin to and from a position with its end extending beyond the surface of the bar, and means for operating the said head and connected blade with a step-by-step movement relative to said bar. 105

5. A combined T-square and section-liner, comprising a cross-head and connected blade, a bar having a sliding connection with said head and provided with pins movably supported within recesses in one side thereof, an operating-bar operatively connected with said pins to move the same to and from a position with their ends extending beyond the surface of the bar, and means for operating the said head and connected blade with a step-by-step movement relative to said bar. 115 120
